UNITED STATES PATENT OFFICE.

JAMES CASSIDY, ARTHUR B. METCALFE, AND SAMUEL J. CASSIDY, OF SYRACUSE,
NEW YORK.

WHEEL AND RAIL LUBRICATOR.

1,097,704.

Specification of Letters Patent. Patented May 26, 1914.

Application filed July 31, 1913. Serial No. 782,377.

To all whom it may concern:-

Be it known that we, JAMES CASSIDY, ARTHUR B. METCALFE, and SAMUEL J. CASSIDY, of Syracuse, in the county of Onondaga, in the State of New York, have invented new and useful Improvements in Wheel and Rail Lubricators, of which the following, taken in connection with the accompanying drawings, is a full, clear, and exact description.

10 This invention relates to certain improvements in wheel and rail lubricators for lubricating curved rails, frogs and other portions of a railway track which are subjected to excessive friction by contact with the wheels of the rolling stock.

15 It is well known that the friction produced by contact between the flanges of the wheels with the ball or head of the rails in passing around curves and also through frogs, automatic switches and like appliances produces excessive wear both upon the flange of the wheel and upon the ball or head of the rail to such an extent as to require frequent and expensive repairs and 25 that this friction also produces more or less objectionable noise particularly in electric railway systems of cities and other congested districts.

Our object, therefore, is to provide simple and practical means for lubricating the 30 contacting portions of the wheels and rails at any point or points along the line of the railway where friction between the rails is liable to produce excessive wear or noise.

35 In other words, we have sought to render this lubrication automatic and positive at the points desired by causing the wheels to travel in contact with a lubricator or lubricant absorbers confined in suitable containers or reservoirs which are relatively fixed in close proximity to the rails in the path 40 of the moving flanges of the car wheels and in proximity to the points of the rails to be lubricated so that as the wheels approach such points, their flanges will automatically 45 take up a part of the lubricant and distribute it to the portions of the rails with which they come in contact.

Another object is to provide means for 50 closing the ends of the containers through which the flanges must pass so as to effectively confine the lubricant absorber therein and at the same time allow the wheels to pass through the upper portion of the

containers without excessive friction therewith.

A further object is to provide means for automatically fitting the absorbent material containing the lubricant into operative position for contact with the flanges of the wheels as the absorbent becomes worn or compressed.

Other objects and uses relating to specific parts of the lubricating system will be brought out in the following description.

In the drawings—Figure 1 is a top plan of a track showing a curve and our improved lubricant containing reservoirs secured to the rails thereof at either end of the curve. Fig. 2 is an enlarged transverse sectional view through one of the rails and adjacent reservoirs taken on line 2—2, Fig. 1. Fig. 3 is an enlarged longitudinal sectional view through the same reservoir.

In order that our invention may be clearly understood, we have shown a single track —1— having a curve —2—, the track being composed in this instance of T-rails —3— secured in the usual manner to ties —4— for supporting the wheels as —A— of the cars which are adapted to move along and upon said track.

The lubricant device forming the subject matter of our present invention comprises a trough-like reservoir —5— having one side secured by suitable bolts —6— to the inner side of the web of the rail —3— for receiving and confining a body —7— of lubricant absorber, such as waste, wicking or equivalent material capable of being saturated with oil or similar lubricant. These reservoirs are preferably secured to the inner sides of both rails just in advance of the points to be lubricated as for example at the ends of a curve so that the flanges of the wheels of the cars or motor traveling in either direction will take up a sufficient quantity of lubricant from the reservoirs to distribute along and lubricate the inner sides of the heads or balls of the rails, it being understood, of course, that a similar result will be produced upon frogs and switch points by properly locating the reservoirs so that the lubricant absorber will come in contact with the flanges of the wheels. The length of the reservoirs is equal to or exceeds the circumferential length of the wheels as ordinarily employed in rolling

stock of rail-ways while the width of the channel in which the lubricant is confined is sufficient to receive the flange of the wheel without friction with the sides of the reservoir.

In order that each reservoir may be securely held in place, its outer side is fitted snugly against the inner face of the web of the rail —3— and between the head and the base flanges thereof so that the bottom is in close proximity to the lower flange while the inner side is of greater vertical depth than the outer side and extends upwardly to approximately the same plane as the upper surface of the head of the rail, thereby producing a confining channel for the lubricant of considerable vertical depth, said channel being open at the top to permit the flange of the wheel to travel therethrough in contact with the lubricant absorbent. Portions of the ends of the reservoir tend upwardly from the bottom to a plane in proximity to the lower face of the head or ball of the rail to allow ample clearance for the passage of the flange of the wheel —A— through the channel without friction with the fixed portions of said ends which serve to additionally confine the lubricant absorbent —7— against endwise displacement from the reservoir.

As a further means for confining this lubricant against displacement from the upper edges of the fixed portions of the ends, we have provided said fixed ends with movable sections —8— which in this instance are hinged at —9— to the fixed end portions and incline upwardly and inwardly therefrom at an angle of less than 45° so as to normally overhang the adjacent portions of the lubricant absorbent —7— or of sufficient width to extend between the inner face of the ball of the rail —3— and inner side of the reservoir with enough clearance to permit them to move freely. In other words, the inner ends of the wings of the end gates —8— are normally disposed in approximately the same plane as the upper surface of the ball of the rail and are yieldingly held in this position by springs —10— as shown more clearly in Fig. 3, the hinged ends of the gates being provided with abutments or limiting stops —11— engaging the upper edges of the fixed portions of the ends of the reservoir to limit their upward swing movement.

The angle of inclination of the gates —8— is such that the wheels of a car may pass over and depress them in either direction, thereby operating not only to confine the oil-saturated waste within the reservoir against endwise displacement but also serving to compress such waste under the action

of the wheels to express the oil therefrom toward the center for contact with the flanges of the wheels.

A follower —12— is movable in the base of the reservoir and spring-pressed upwardly by springs —13— to force the oil-saturated waste upwardly and to keep its upper surface in the path of the flanges of the traveling wheels.

It is now apparent that the main feature of our invention consists in running a channeled reservoir along and in close proximity to the ball or head of the rail at the inner side thereof with its open side in the path of the flanges of the wheels and containing an oil-saturated body of waste or equivalent material disposed with its upper surface in the path of the wheel flange so that the wheel flanges rolling through the channels will take up oil throughout its periphery and distribute the same to the rail at the curves or other places where lubrication is necessary.

What we claim is:

1. A device for lubricating rails and the flanges of car wheels comprising a reservoir secured to the rail and containing a body of lubricant absorbent having its upper surface disposed in the path of the wheel flange as it moves along the rail.

2. A lubricating device for rails and wheel flanges comprising a reservoir arranged along the inner side of the rail and open at the top and containing a lubricant in the path of the flange of the wheel as it moves along the rail.

3. A lubricating device for rails and wheel flanges comprising a reservoir arranged along the inner side of the rail and open at the top and containing a lubricant in the path of the flange of the wheel as it moves along the rail, and a follower in the reservoir spring-pressed upwardly for forcing said absorbent body toward the top of the reservoir.

4. A device for lubricating rails and wheel flanges comprising a reservoir secured to the inner side of the rail and containing an oil absorbent having its upper surface disposed in the path of the wheel-flange as the wheel moves along the rail, and movable end gates on the ends of the reservoir for confining the absorbent against endwise displacement.

In witness whereof we have hereunto set our hands.

JAMES CASSIDY.
ARTHUR B. METCALFE.
SAMUEL J. CASSIDY.
